MANUFACTURE AND JOINING OF ARTICLES
OF CONCRETE AND THE LIKE

Bohuslav Rumík, Prague, Czechoslovakia

Application January 30, 1931, Serial No. 512,467
In Czechoslovakia June 11, 1930

4 Claims. (Cl. 25—155)

The subject matter of the invention is a method as well as an apparatus for the production of articles of all kinds, of concrete, ferro-concrete, asbestos cement and the like, especially of tubes. 5 The apparatus according to the present invention is illustrated by the accompanying drawing, of which Fig. 1 shows the whole arrangement with the mould in cross-section, Figs. 2 and 3 show the mould in cross-section and longitudinal 10 section respectively, Fig. 4 shows the iron reinforcement.

The mould 1, which is in a plurality of parts and is capable of being dismantled, may be made entirely closed or partly open; it is provided with 15 end walls 2. The core 3, which serves for forming the hollow space in the body, may be made in various ways—e. g., cylindrical, conical or prismatic.

The apparatus further comprises a compressed air container 4, into which the compressed air is driven by an air compressor (not shown), and a container 5 for concrete, the top opening of which is closed by a lid 6 that acts as a check valve. The compressed air container 4 is connected with the concrete container 5 by a compressed air pipe 7. The concrete container 5 is connected to the mould 1 by means of a pipe 12 provided with a cock 35.

The method is carried out as follows:— 30 The liquid concrete is driven, by the action of the compressed air, from the container 5, through the pipe 12 into the mould 1. The concrete set in motion has a resistance to overcome which is not constant but frequently fluctuates during 35 working. At the commencement of working it is often necessary to set the concrete in motion by an increased compressed air action and immediately after to reduce the air pressure, in order to avoid a local clogging of the mould 1. On continued filling of the mould, it is necessary to increase the air pressure. After the filling of the mould is completed, it is frequently necessary to increase the air pressure in the container 5 still further in order to compress the concrete in the 45 closed mould and to drive out the excess of water. The excess of water then flows out through the openings 14, that are capable of being shut off, provided in the mould 1.

The magnitude of the air pressure in the container 5 is further dependent upon the thickness of concrete and the length of the hollow body, upon the height from which the concrete is delivered, upon the frictional resistance in pipe 12, and upon the water content of the concrete. This 55 magnitude of air pressure is controlled by using a

manometer 34. The emptying of the concrete container 5 takes only a few minutes or seconds. Accordingly, the air pressure in the concrete container 5 must very rapidly be made to conform to the fluctuating resistance of the concrete. 5

In order to obtain the correct and immediate alterations of the pressure of the compressed air in the concrete container 5 with respect to the fluctuation of the resistance of the concrete being delivered, the compressed air pipe 7 is provided 10 with a throttle valve 15 and a reducing valve 16.

After the filling of the mould 1 with concrete has been effected, a rapid setting of the outer layers of the concrete body is effected by heat. For this purpose there are provided, at the inner 15 surface of the mould 1, longitudinal channels 28 into which steam, hot air or the like can be fed. The setting of the concrete proceeds to the extent to which the heat spreads from the outer to the inner surface of the concrete body. At 20 the instant in which the outer layer of the concrete is in the hard condition, the inner concrete layer is still plastic. The already hard outer layer of concrete forms a firm base to which the still plastic inner concrete layer 25 adheres. The core 3 can be withdrawn at this instant. The still plastic inner layer of concrete offers only very little resistance on the withdrawal of the core 3. The proper length of heating of the outer surface of the concrete is 30 predetermined empirically.

On the production of concrete bodies in which the formation requires a smooth inner surface, the withdrawal of the core 3 should be proceeded with when the inner layer of concrete is very 35 near to or just at the setting stage. If this instant is missed, the set concrete embraces the core so firmly that its withdrawal would be impossible.

In order to ascertain the correct point of time 40 for withdrawing the core, the latter is occasionally or continuously rotated. Owing to the continued setting of the concrete, the friction of the core in the concrete increases and the power necessary for the rotation of the core 3 accordingly also increases. This growing consumption of power is measured—e. g., with the aid of an ammeter. As soon as this consumption of power reaches an empirically predetermined degree, the 45 core 3 is withdrawn from the concrete.

By heating the concrete, the core is also heated and its diameter thus increased. If the core, before being withdrawn from the concrete, is cooled by admission of cold water or the like, it 55

contracts to its original diameter and its withdrawal is thus further facilitated.

In order that the mould which is made of a number of parts should not come apart during the filling of the concrete body owing to the internal pressure then developed, the mould is secured by a rope 29 which is helically wound on its outside and which is fastened at its two ends to hooks 30 fitted in the outside of the mould (Fig. 3).

10 In the case of the production of concrete bodies with iron reinforcements 31—32, the latter are fixed in position by rings of concrete 33 (Figs. 2 and 4) mounted or pressed on at suitable intervals which rest against the core during the filling 15 of the mould and serve as guides for the core during its removal, being embedded with their outer portions in the hardened outer layer of the concrete body.

10 The concrete body is left in the mould until the hardening is ended. The rope 29 is then unfastened and removed and the mould is dismantled.

What I claim and desire to secure by Letters Patent of the United States of America is:—

1. A method for facilitating the withdrawal 25 of the core during the manufacture of hollow

articles of all kinds made of concrete, ferro-concrete, asbestos-cement and the like, especially of tubes, comprising heating only the outer concrete layer of the body in order to accelerate the setting of the outer concrete layer with regard to that of the inner concrete layer.

2. A method according to claim 1 wherein during the heating of the surface of the concrete, the core is occasionally or continuously rotated and the consumption of power necessary for rotating the core is measured for the purpose of checking the progress of the setting of the concrete.

3. A method according to claim 1 wherein the core is withdrawn from the concrete body at the point of time at which the outer surface is hard and the inner surface is still soft.

4. A method according to claim 1 applicable to the manufacture of hollow articles of ferro-concrete containing metal reinforcing rods, wherein reinforcements are fixed in position by rings of concrete mounted thereon, which rest against the core during the filling of the mold, and serve as guides for the core during its removal.
